UNITED STATES PATENT OFFICE.

HIRAM W. STETSON, OF BLACK BROOK, NEW YORK.

BEDCLOTHES-HOLDER.

SPECIFICATION forming part of Letters Patent No. 387,376, dated August 7, 1888.

Application filed September 3, 1887. Serial No. 248,677. (No model.)

To all whom it may concern:

Be it known that I, HIRAM W. STETSON, of Black Brook, Clinton county, in the State of New York, have invented a certain new and 5 useful Improvement in Bedclothes-Holders, of which the following is a specification.

My device is mounted adjustably on the foot-board or corresponding part of a bedstead. It is provided with a clamp extending across 10 the whole or the principal portion of the foot of the bed, adapted to hold the clothes by pressing them downward upon the mattress. The device is simple. A single spring holds 15 the clamp down upon the bedclothes to retain them when required, and also holds the clamp up out of the way when the bed is to be made up. The device acts with a yielding force, adapted to accommodate itself to varying thicknesses of the bedclothing or mattress. 20 The position of the whole is adjustable upward and downward.

The accompanying drawings form a part of this specification, and represent what I consider the best means of carrying out the invention.

Figure 1 is a vertical section of a portion of a bedstead having this device. Fig. 2 is an elevation of certain portions partly in vertical section. The device is in the position shown 30 by dotted lines in Fig. 1. Fig. 3 is a vertical section of a bedstead, showing the device in elevation. This figure is on a much smaller scale.

Similar letters of reference indicate corresponding parts in all the figures where they occur.

A is a portion of the bedstead, B a portion of the bedclothes, and C a portion of the mattress, all of any ordinary or suitable character.

40 D is the foundation-board. It is held to the bedstead A by screws E, inserted through slots d, so as to allow the board D and its connections to be adjusted upward and downward to accommodate the device to different thicknesses of mattress or to a greater or less number of mattresses or supports therefor.

D' D' are brackets screwed or otherwise firmly secured to the board D and supporting the knuckles M' of the clamp M. There are 45 three of the brackets D'—one near each end and one in the middle of the board D. There

are three corresponding knuckles M' on the clamp M.

M' is an eye screwed or otherwise secured on the clamp M in the position shown.

55

P is a band of thin metal—or it may be leather, webbing, or other flexible material—which extends downward from the eye M' and communicates to the clamp M the force of the single spring employed to hold the clamp down 60 and up as required. The band P extends partially around the pulley G, fixed on the shaft G', and is subject to the force of a spring, K, which is coiled around the shaft G', and engaged one end in a hole, g, in the pulley G 65 and the other in a hole, h, in a sleeve, H, which loosely incloses the shaft and spring, and is provided both with a journal, H', and an arm, H'', which latter is parallel to H', but shorter.

I and J are brackets fixed in the required 70 position on the board D. The bracket I simply receives and supports the shaft G'. The bracket J is provided with a central hole, J', which receives the journal H', and with a series of holes, J'', one of which receives the arm 75 H''. The spring K exerts a longitudinal force.

It also exerts a turning force, according as it is wound up or adjusted in applying the parts together. The number of coils in the spring K should be sufficient to allow a liberal range 80 of motion, so that it exerts a nearly constant tension on the band P. When the clamp M is let down into the position shown in strong lines in Fig. 1, it holds the bedclothing B reliably in place on the mattress C. When, on 85 the contrary, the clamp M is raised by the attendant into the position shown in dotted lines in Fig. 1, the spring K yields and allows the pulley G to turn and the band P to be drawn off the required extent. The parts are so proportioned that when the clamp is thrown up 90 the band moves past the axis of motion of the clamp, and by its tension holds the clamp up with sufficient force to overcome its gravity.

In putting the parts together the sleeve H 95 is turned to wind up the spring, and on being liberated the thrusting force of the spring engages the arm H'' in the proper hole J''. When at any period afterward it is desired to adjust the force of the spring, so that the pulley G 100 shall pull on the band P with greater or less force, it is simply necessary to take hold of the

5 sleeve H with sufficient force and move it end-
wise toward the pulley G, so as to disengage the
arm H² from its hole J², and turn the sleeve H
partially around and again engage the arm H²
in a different hole J².

10 Modifications may be made in the details
without departing from the principle or sac-
rificing the advantages of the invention. The
clamp M is represented as extending consid-
erably beyond the knuckles M' toward the foot
15 of the bed and as matching closely against a
cornice, D*, near the top of the board D. I
prefer this construction, as also the curving of
the adjacent outline of the brackets D', so that
the clamp shall run close thereto as it is raised
and lowered; but these points are not essential.

I claim as my invention--

1. In an automatic bedclothes-holder, the
clamp M, turning on centers M' at a proper
20 height above the bed, in combination with the
band P, connected at one end to said clamp,
and a spring, K, connected to the other end of

said band and exerting a tension on one side
or the other of the axis M', according as the
clamp is elevated or depressed, so as to hold 25
the clamp forcibly downward and also forcibly
upward, as required, all substantially as herein
specified.

2. In a bedclothes - holder, the clamp M,
turning on centers M', in combination with 30
the band P, pulley G, shaft G', and helical
spring K, adapted to hold the clamp either
elevated or depressed, and adjusting means,
as the slots d and screws E, to adjust the clamp
35 upward and downward, substantially as herein
specified.

In testimony whereof I have hereunto set my
hand, at Black Brook, Clinton county, New
York, this 26th day of August, 1887, in the
presence of two subscribing witnesses.

HIRAM W. STETSON.
